US0D1084817S

(12) United States Design Patent (10) Patent No.: US D1,084,817 S
(45) Date of Patent: * Jul. 22, 2025

(54) HANDLE

(71) Applicant: Shenzhen City Sheng Hua sun Technology Co. Ltd., Guangdong (CN)
(72) Inventor: Shanhua Liang, Guangdong (CN)
(73) Assignee: Shenzhen City Sheng Hua sun Technology Co. Ltd., Shenzhen (CN)

() Term: 15 Years

(21) Appl. No.: 29/997,036

(22) Filed: Apr. 3, 2025

(51) LOC (15) Cl. 08-06
(52) U.S. Cl.
USPC D8/313

(57) CLAIM

The ornamental design for a handle as shown and described.

DESCRIPTION

FIG. 1 is a perspective view of a handle showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is a bottom plan view thereof.

The broken lines depict portions of the handle and form no part of the claimed design.
